ABRASIVE SHEET HOLDER

Robert Lequeux Smith, San Diego, Calif.

Application November 26, 1945, Serial No. 630,766

1 Claim. (Cl. 51—187)

1

My invention relates to an abrasive sheet holder for use in various abrading operations such as knife sharpening, honing and sanding or the like and the objects of my invention are:

First, to provide an abrasive sheet holder of this class in which the abrasive sheet is readily replaceable;

Second, to provide an abrasive sheet holder of this class in which various grades of abrasive may be used in connection therewith for various grades of finish as desired;

Third, to provide an abrasive sheet holder of this class which is particularly useful in sharpening knives;

Fourth, to provide an abrasive sheet holder of this class having novel abrasive sheet holding means;

Fifth, to provide an abrasive sheet holder of this class having novel hand guard means for maintaining the abrasive sheet holder in certain locked position;

Sixth, to provide an abrasive sheet holder of this class in which the holding means is readily removable from the main body of my abrasive sheet holder;

Seventh, to provide an abrasive sheet holder of this class in which the abrasive sheet holder member is surrounded at opposite ends of the abrasive sheet by securing means preventing inadvertent release of the abrasive sheet; and

Eighth, to provide an abrasive sheet holder of this class which is very simple and economical of construction, efficient in its action and which will not readily deteriorate or get out of order.

With these and other objects in view as will appear hereinafter, my invention consists of certain novel features of construction, combination and arrangement of parts and portions as will be hereinafter described in detail and particularly set forth in the appended claim. Reference being had to the accompanying drawings and to the characters of reference thereon, forming a part of this application in which:

Fig. 1 is a fragmentary longitudinal sectional view of my abrasive sheet holder. Fig. 2 is a transverse sectional view thereof, taken from the line 2—2 of Fig. 1. Fig. 3 is a transverse sectional view taken from the line 3—3 of Fig. 1, showing a part in elevation to facilitate the illustration and showing by dash lines a varying position of the hand guard in connection therewith. Fig. 4 is a transverse sectional view taken from the line 4—4 of Fig. 1 and Fig. 5 is a fragmentary longitudinal sectional view of a modified form of my abrasive sheet holder. Similar characters

of reference refer to similar parts and portions throughout the several views of the drawings.

The body member 1, sheet holder member 2, surrounding member 3, abrasive sheet 4, and the hand guard 5 constitute the principal parts and portions of my abrasive sheet holder.

The body member 1, as shown in Figs. 1 and 2 of the drawings, is cylindrical in form and is provided with a longitudinal slotted portion, 1a, open at one side and converging inwardly toward the middle portions thereof, as shown best in Fig. 2 of the drawings. This slotted portion, 1a, extends the full length of the body member 1, and removably positioned therein is the sheet holder member 2 which is substantially V-shaped in cross section, as shown in Fig. 2 of the drawings, and is arranged to wedge the edge portions 4a and 4b of the abrasive sheet 4 into the slotted portion, 1a, all as shown best in Fig. 2 of the drawing. It will be noted that the abrasive sheet 4 substantially surrounds the body member 1 and is forced into snug engagement therewith by means of the wedged relationship of the holder member 2 in engagement with the edge portions 4a and 4b of the abrasive sheet 4. Fitted over the body member 1 and the sheet holder member 2 is the surrounding member 3. This surrounding member 3 is arranged in the form of a cap and provides a smooth spheroid end for my abrasive sheet holder and also serves to retain the forward end of the sheet holder member 2 firmly in the slotted portion 1a of the body member 1. The hand guard 5, as shown in Figs. 1 and 3 of the drawings, is preferably made of heavy gauge resilient wire and operates as a surrounding member for the body member 1 and the sheet holder member 2. As shown in Fig. 3 of the drawings, the body member 1 is provided with a flat portion, 1b, in opposed relation to the open side of the slotted portion, 1a, operating as a detent in connection with the resilient straight side, 5a, of the hand guard 5. It being noted that the flat portion, 1b, is an annular groove portion, 1c, formed in the body member 1 and sheet holder member 2, which maintains the hand guard 5 in longitudinal disposition relatively to the body member 1 and the sheet holder member 2. The hand guard 5 normally engages the outer side of the sheet holder member 2, retaining the same in the slotted portion, 1a, of the body member 1, and when pivoted, as shown in Fig. 3 of the drawings, is spread permitting removal of the sheet holder member 2, all as indicated by dash lines in Fig. 3 of the drawings.

In Fig. 4 of the drawings, the surrounding

member 3 is shown in engagement with the body member 1 and the sheet holder member 2, surrounding the ends thereof forwardly of the abrasive sheet 4.

The operation of my abrasive sheet holder is substantially as follows:

When placing the abrasive sheet 4 on the body member 1, the edge portions 4a and 4b are placed over the slotted portion, 1a. The sheet holder member 2, at its forward end, 2a, is shouldered against the edge portion, 3a, of the surrounding member 3. When this sheet holder member 2 is forced downwardly into the slotted portion, 1a, of the body member 1, it tightens and wedges the edge portions 4a and 4b of the abrasive sheet 4 tightly in the slotted portion, 1a, of the body member 1, as shown best in Fig. 2 of the drawings. At opposite edges of the slotted portion, 1a, the body member 1 is provided with radius portions, 1d and 1e, which permit the movement and tightening of the abrasive sheet 4 therearound, when the holder member 2 is forced into the slotted portion 1a. As shown in Fig. 3 of the drawings, the hand guard 5 is in the dash line position whereupon the end portions 5c and 5d are forced apart permitting the sheet holder member 2 to pass therebetween. The inside diameter of the annular groove portion, 1c, is greater than the distance from the flat portion, 1b, to the side of the sheet holder member 2, therefore the turning of the hand guard 5 into the dash line position, as shown in Fig. 3, causes the end portions 5d and 5c to be spread, all as shown best in Fig. 3 of the drawings.

As shown in Fig. 1 of the drawings, the sheet holder member 2 is surrounded at its forward end and rearwardly of the abrasive sheet 4, thus preventing any inadvertent removal of the sheet holder member 2.

The modification, as shown in Fig. 5 of the drawings, is provided with a body member 6 and a sheet holder member 7, having substantially the same structural characteristics as the body member 1 and the sheet holder member 2, shown in Figs. 1 to 4, inclusive, of the drawings. This modified structure, as shown in Fig. 5 of the drawings, is also provided with a surrounding member 8, which is substantially the same in structure as the surrounding member 3, shown in Figs. 1 to 4, inclusive. The modification, as shown in Fig. 5, also incorporates an abrasive sheet 9 arranged in similar relationship to the abrasive sheet 4 as shown in Figs. 1 to 4 of the drawings. This modified structure, as shown in Fig. 5, however is provided with a handle 10 having a longitudinal bore 10a therein, which surrounds the body member 6 and the sheet holder 7 and is fitted over the rear end thereof, main-

taining the connected relationship of the body member 6 and the sheet holder member 7 in substantially the same manner as does the hand guard member 5 of the principal structure, as shown in Figs. 1 to 4 of the drawings.

Though I have shown a particular construction, combination and arrangement of parts and portions, and a certain modification, I do not wish to be limited to the particular construction, combination and arrangement nor to the modification, but desire to include in the scope of my invention the construction, combination and arrangement and modification, substantially as set forth in the appended claim.

Having thus described my invention, what I claim as new and desire to secure by Letters Patent is:

In an abrasive sheet holder of the class described, the combination of a cylindrical body member having longitudinal slot in one side wall thereof, a surrounding member fitted over one end of said body member, an abrasive sheet surrounding said body member and extending at its opposite edges into said longitudinal slot, a sheet holder member wedged into said slot intermediate opposite edges of said abrasive sheet and having its one end inwardly of said surrounding member, and a second surrounding member at the opposite end of said abrasive sheet from said first surrounding member arranged to maintain said sheet holder member in said slotted portion of said body member, said second surrounding member having laterally extending portions forming hand guard means, said second surrounding member retained in an annular groove in said body member having a flat portion operating as a detent, said second mentioned surrounding member having a straight side portion engaging said detent portion and abutted opposite ends extending some distance from said detent portion at one side of said body member.
